[57] CLAIM

The ornamental design for a top cover with discharge orifice for the outdoor unit of an air conditioning split system, as shown and described.

DESCRIPTION

FIG. 1 is a perspective view of a top cover with discharge orifice for the outdoor unit of an air conditioning split system, showing our new design;

FIG. 2 is a top plan view thereof;

FIG. 3 is a front elevation view thereof, of which the rear elevational view is a mirror image;

FIG. 4 is a bottom plan view thereof;

FIG. 5 is a right side elevational view thereof; and,

FIG. 6 is a left side elevational view thereof.

The broken-line showing of a condensing unit and grate, in FIG. 1, is for illustrative purposes only, and forms no part of the claimed design.
